CIRCUIT CONTROLLER

Harry J. Lingal, Forest Hills, Pa., assignor to
Westinghouse Electric Corporation, East Pitts-
burgh, Pa., a corporation of Pennsylvania

Application February 16, 1945, Serial No. 578,209

5 Claims. (Cl. 200—153)

1

This invention relates generally to electric circuit controllers, and more particularly to operating and control mechanism for such controllers.

Electric switching devices for certain applications are required to operate at extremely high speed, and this presents the problem of preventing rebound of the switch contacts, especially when the high-speed operation is the circuit closing operation, in order to avoid arcing.

Accordingly, one object of this invention is to provide novel means for preventing rebound of a high-speed switch element when its movement is suddenly stopped.

Another object of this invention is to provide novel impact-actuated means for positively holding a high-speed switch member against rebound, when said element is suddenly stopped.

Another object of this invention is to provide novel means for absorbing at least a part of the kinetic energy in a high-speed switch member when the movement of said member is halted.

Another object of this invention is to provide novel actuating means for closing a disconnect switch at high speed.

A more specific object of this invention is to provide a disconnect switch with actuating means to open the switch and concurrently store energy which is suddenly releasable, to effect high-speed closing of the switch.

Still another object of this invention is to provide a disconnect switch with actuating means to open the switch and concurrently store energy which is suddenly releasable to effect high-speed closing of the switch, free of the actuating means.

A further object of this invention is to provide a novel connection between parts of an operating mechanism for a circuit interrupter.

These and other objects of this invention will become more apparent upon consideration of the following detailed description of preferred embodiments thereof, when taken in connection with the attached drawings, in which:

Figure 1 is a side elevation view of a three-pole switch assembly embodying this invention, with certain of the parts shown in section, and with the switch blades removed;

Fig. 2 is an end elevation view of the switch assembly shown in Fig. 1, with certain of the parts broken away or shown in section to better illustrate the construction;

Fig. 3 is a partial elevation view of the actuating mechanism for the switch shown in Figs. 1 and 2;

2

Fig. 4 is a partial end elevation of the mechanism illustrated in Fig. 3;

Fig. 5 is a side elevation view, partially in section, of a modified operating mechanism for a switch assembly, such as that shown in Figs. 1 and 2; and

Fig. 6 is a sectional view of a part of the operating mechanism illustrated in Figs. 1 and 2.

This invention is illustrated on the drawings 10 as being embodied in a three-pole disconnecting switch structure which is adapted to be supported on an open framework, comprising spaced pairs of spaced upright supports 2 connected at their lower ends by longitudinally extending angle irons 4. A suitable base 6 of any desired material, may 15 be confined between angle irons 4 at the lower ends of supports 2. Intermediate the ends of upright supports 2, there is provided, at each side of the upright supports, angle irons 8 extending substantially transversely of the upright supports, and secured thereto. The transverse angle irons 8 support a longitudinally extending channel structure 10, substantially intermediate between 20 each pair of upright supports 2.

At the upper ends of upright supports 2, there 25 is provided at each side a longitudinally extending angle iron 12 for connecting the upper ends of upright supports 2. The angle irons 12, in turn, are adapted to support spaced vertically extending angle irons 14 of smaller size, and these are 30 connected at their upper ends at each side by longitudinally extending angle irons 16. The smaller angle members 14 and 16 are for the purpose of supporting spaced barrier plates 18, 35 of fiber or a molded insulating material, to define spaced compartments 17 in each of which there is supported a disconnecting switch.

Each compartment 17 is provided with a base 20 secured to angle irons 12, with the base 20 40 being of any desired insulating material, such as fiber or a molded insulating material. At one end of base 20, there is mounted a hinge contact structure 22 having a tubular terminal extension 24 at one side, in which a line conductor may be 45 secured. Hinge contact structure 22 supports pivot means 26, for movably supporting a switch blade 28 for pivotal movement into and out of engagement with a contact jaw structure 30 secured at the other end of base 20. Contact jaw 50 structure 30 is also provided with a tubular terminal extension 22 for receiving a line conductor.

Each switch blade 28 is provided with its own operating rod 34 pivotally connected thereto intermediate the ends of the blade, as at 35. Operating rods 34 should be of insulating material,

such, for example, as wood or a molded insulating material. The lower end of each operating rod 34 extends through an opening in the upper end of an open rectangular frame 36, adapted to be secured at its lower end on longitudinally extending channel support 10. A blade closing spring 38 is mounted within each frame 36, and is adapted to react between the top of the frame and a washer 40 secured adjacent the lower end of each operating rod 34. The operating rod 34 at the extreme right, as viewed in Fig. 1, is adapted to be actuated in a direction to open switch blade 28, by an operating lever 42. Operating lever 42 is of substantially inverted U shape in form, and includes spaced sides 44 and an integral connecting portion 46. The operating lever 42 is pivotally supported as at 48, on a supporting bracket 50 mounted on the frame structure, and is operatively connected with the adjacent operating rod 34, as by a pivot pin 52 at one end of the lever, extending through the lower end of this operating rod. The other end of operating lever 42 is adapted to be connected with an actuating rod 56, by means of a pivot pin 54.

For the purpose of actuating switch blades 28 in a direction to open the disconnect switches, there is provided a solenoid operated trip-free mechanism, which is generally similar to that disclosed in the patent to J. B. MacNeill et al., No. 2,144,502, for Latching mechanism, and issued January 17, 1939, to the same assignee of this invention. This mechanism includes a split trip-free lever 58 pivotally connected intermediate its ends as at 60 with the lower end of actuating rod 56. Trip-free lever 58 is pivotally connected at one end thereof with solenoid lever 64, as by a pivot pin 62, and is located between the sides of solenoid lever 64, which is also of split construction. The solenoid lever structure 64 is pivotally supported as at 66 between spaced supporting members 68, secured on solenoid frame 70.

Trip-free lever 58 carries a trip-free pin 72 (Fig. 6), which, in the position of the parts shown in Fig. 1, is disposed substantially in alignment with supporting pivot 66 for solenoid lever 64, and is adapted to be engaged by a slip-off latch 74, pivotally mounted on the solenoid supporting frame as at 76. Slip-off latch 74 is provided with a light biasing spring 78 to normally bias it to its latching position.

A back-up latch 76 which is pivotally mounted on the solenoid frame structure, as at 78, is provided for normally holding slip-off latch 74 in latching position. A trip coil 80 is provided for releasing back-up latch 76 when energized, by causing movement of a plunger 82 upwardly, as viewed in Fig. 6.

Solenoid frame 70 supports a solenoid coil having a plunger adapted to be drawn downwardly when the coil is energized, to move solenoid lever 64 downwardly by means of connecting links 84 pivotally connected with solenoid lever 64, and with the solenoid plunger. The switches are illustrated in the drawings in their closed circuit position, being held at this position by closing springs 38. When it is desired to open the disconnecting switches, the solenoid supported by frame 70 is energized to exert a downward pull on solenoid lever 64 and cause it to move clockwise relative to its supporting pivot 66. Trip-free lever 58 will be carried along with solenoid lever 64, and thus move actuating rod 56 downwardly to rotate operating lever 42 in a clockwise direction relative to its supporting pivot 48. Such rotation of operating lever 42 causes operating

rods 34 to move upwardly, and consequently switch blades 28 are caused to rotate in a counterclockwise direction, as viewed in Fig. 2, to an open circuit position. During this opening of the switch blades, closing springs 38 are loaded. The opening movement of the blades and actuating mechanism continues until pivot pin 62, which pivotally connects trip-free lever 58 and solenoid lever 64, engages the notch in latch lever 86 pivotally mounted on solenoid supporting frame 70, with latch lever 86 biased to a latching position by a light spring 80.

Now if it is desired to close the switch, trip coil 80 is energized to move back-up latch 76 in a counterclockwise direction and thus remove the support for slip-off latch 74. Closing springs 38 will then be effective to move switch blades 28 and actuating rod 56 in an upward direction, with trip-free lever 58, having been released from slip-off latch 74, pivoting in a clockwise direction about pivot pin 62, free of the opening solenoid mechanism. This permits closing springs 38 to close the switches at an extremely rapid rate. The switches illustrated are used to close circuits in which extremely high currents, on the order of 100,000 amperes are flowing, at relatively high voltages, such as about 10,000 volts. It will be obvious, that in order to prevent excessive arcing, it is essential that the closing movement of the switches be extremely rapid, and it is for this reason that the closing springs 38 are made to be trip-free of the switch opening means, so as to be relatively unimpeded during a switch closing operation.

The trip-free operating mechanism is adapted to automatically condition itself for a circuit opening operation immediately after a circuit closing operation, because it will be observed that during closing and consequent pivotal movement in a clockwise direction a trip-free lever 58 about pivot pin 62, that pin 87 on the trip-free lever will engage latch lever 86 to release pin 62. This then permits reset spring 82, which reacts between the top of solenoid supporting frame 70 and a pivot pin 94 provided on solenoid lever 64, to move the solenoid lever and trip-free lever 58 to the positions shown in full lines in Fig. 1. Such resetting movement of the levers entails counter-clockwise movement of solenoid lever 64 under the influence of reset spring 82 about its supporting shaft 86, while moving trip-free lever 58 in a counterclockwise direction about its pivot 60 on actuating rod 56, until trip-free pin 72 is reengaged by slip-off latch 74. The parts are then reset for a circuit opening operation, such as described above.

An operating bellcrank lever 95 may be pivotally mounted on a support at the top of the solenoid operating mechanism and be provided with a slot for receiving pivot pin 60 on the lower end of actuating rod 56, and be connected with a rod 103 for the purpose of actuating auxiliary switches or the like 96 in response to operation of disconnect switch blades 28. Solenoid supporting frame 70 may also be provided with spaced supporting brackets 97 for supporting a manually operable jack or the like (shown in dot and dash lines) which may be employed to open the switches in the event of failure of the solenoid operating mechanism. A control panel 98 may also be conveniently mounted between a pair of upright supports 2, such as the intermediate pair illustrated.

While the operating mechanism thus far described is capable of actuating the switch blade

28 adjacent thereto, all of the switch blades 28 are adapted to be operated in unison by common operating mechanism, which includes a pair of longitudinally extending connecting links 100 pivotally mounted at one end by a pivot pin 104 on integral extensions of operating lever 42. These connecting links 100 are adapted to be pivotally connected as by pivot pins 104, with operating bell cranks 102 for each of the other disconnect switches. The operating bell cranks 102 are adapted to be pivotally mounted on supporting brackets as at 106, with one arm pivotally connected with the operating rod 34 of the associated disconnect switch. It will be obvious that operation of operating lever 42 will cause similar movement of bell cranks 102, and consequently simultaneous opening and closing of all three of switch blades 28.

Since the closing movement of switch blades 28 is extremely rapid, due to the unimpeded force exerted by closing springs 38, and since the blades are brought to an abrupt stop when at closed circuit position in engagement with contact jaw structures 30, it is desirable that at least some of the shock of this abrupt halt in blade movement be absorbed by a shock-absorbing means, and for this purpose there is illustrated a dashpot energy-absorbing means associated with each switch operating rod 34. Each dashpot structure includes a dashpot cylinder 108 supported beneath its associated operating rod 34, and having a dashpot piston 110 therein biased to an upper position in the cylinder as by a compression spring 112. The upper limit of movement of piston 110 is determined by engagement of a shoulder 114 provided on the piston, with the lower one of a series of spaced baffles 116 provided in the upper end of dashpot cylinders 108. Each dashpot piston 110 is provided with a connecting rod 111 extending through the closed upper end of the cylinder, and each connecting rod 111 has a head 118 thereon at its outer end. It will be observed that piston rod 111 is provided with a series of tapered portions corresponding in number to the number of baffles 116, for a purpose to be described.

In the closed circuit position of disconnect switch blades 28, it will be observed that the lower end of each operating rod 34 is in engagement with the head 118 of its associated dashpot piston rod, to hold the piston at a position closely adjacent the lower end of its dashpot cylinder 108. When the switches are opened, dashpot piston 110 is moved by its spring 112 to its upper position defined by shoulder 114 and the lower baffle plate 116. Operating rods 34 in opening switch blades 28 travel beyond the upper limit of movement of dashpot operating heads 118, so that when the switches are permitted to be closed at a high rate by closing springs 38, the greater part of the closing movement will be unimpeded, as previously described, and only after considerable momentum and kinetic energy has been built up will the lower ends of operating rods 34 engage heads 118 of the dashpot pistons, to move the pistons downwardly and exert a braking action on the closing movement of switch blades 28. Since the switches are of the air type, it is necessary to seal dashpot cylinders 108, and in order to prevent pumping of liquid sealed within the dashpots through the clearance between dashpot piston rod 111 and the aperture through which it extends, during the sudden downward movement of the dashpot piston when engaged by operating rods 34, baffles 116 are provided to

impede movement of liquid upwardly in the dashpot cylinders toward the opening through which the piston passes, and it will be noted that as the dashpot piston moves downwardly, the clearances between baffles 116 and the piston rod decreases, due to the movement of the large ends of the flared portions of the piston rod into the openings in the baffles.

Although energy-absorbing dashpots are employed, as described above, these cannot be used to absorb all the energy in the moving switch blades 28 and actuating mechanism during the circuit closing operation, because it is necessary that the whole operation occur at high speed, since in handling the high currents at the high voltage previously mentioned, fast closing is essential even between the time initial engagement of the blades and their contact jaw structures 30 occurs, and the time the blades are fully inserted in these jaw structures. Moreover, it has been found that the relative movement of the blades between contact jaw structures 30 produces arcing, and consequently it is imperative that this be reduced to a minimum, and especially that rebound of the blades is prevented after a circuit closing operation. In order, therefore, to prevent such rebound of the blades, there is provided a rebound preventing latch 120 for the outer end of each connecting link 100. This latch is best illustrated in Fig. 3, wherein it is shown as pivoted on a pivot pin 122 mounted on frame structure 36. A rebound preventing latch 120 is provided at each side of frame 36 for each connecting link 100, but only one is illustrated. Each latch 120 is provided with an angularly extending projection 124 adapted, in the closed circuit position of the switches, to be engaged by the head of a bolt 126 mounted on the outer end of each actuating link 100, and maintained in an adjusted position by means of a lock nut 128. Each latch 120 is also provided with a latch projection 130, which in the closed circuit position of the switches is adapted to be positioned just below the extended ends of the adjacent pivot pin 104. In operation, when the switches are opened in the manner previously described by the solenoid operating mechanism, latch levers 120 are adapted to rest on the heads of stop bolts 134 mounted in frame structure 36, and maintained at an adjusted position by a lock nut 136. When trip coil 80 is energized to permit closing springs 38 to close the disconnect switches at a high speed, bolts 126 on the outer ends of connecting links 100 engage projections 124 of the rebound preventing levers substantially at the end of switch closing movement, to impart a blow on the latches 120 to cause them to rotate in a counterclockwise direction about their supporting pivots 122, and bring latch projections 130 to a position wherein they engage pivot pins 104, so that any tendency of the switch blades and actuating mechanism to rebound when their circuit closing movement is suddenly halted, will be positively prevented by the presence at that time of latch projection 130 in engagement with the ends of pivot pin 104, as this positively prevents retrograde movement of connecting links 100, and consequently of switch blades 28. If there is no rebound of the mechanism or switch blades, or after attempted rebound has occurred, the rebound preventing latch levers 120 will then be free to drop down to the position where they are engaged by bolts 126.

In Fig. 5 of the drawings, there is illustrated a modification of actuating mechanism connect-

ed between switch blades 28 and actuating rod 56 of the solenoid mechanism, for providing ready adjustment, so that simultaneous movement of the blades of each switch can be accurately and easily obtained. For this purpose, there is mounted on a transversely extending support 138, a bearing structure 140 for rotatably mounting a common actuating shaft 142, which is of an irregular shape in cross section, such, for example, as the D-shape illustrated. Actuating rod 56 is adapted to be connected to shaft 142 by means of a crank 144, and the shaft is provided with spaced cranks 147 for each disconnect switch blade, and these cranks are operatively connected with the respective blades by means of operating links 148. Each of the cranks 144 and 147 is provided at its inner end with a slot 146, having at opposite sides thereof circular depressions 150 for receiving shaft 142. The extreme inner ends of each of the cranks are provided with a bolt 152 connecting opposite sides of slot 146, and a sleeve 154 of resilient compressible material, such as rubber or the like, is adapted to be inserted between shaft 142 and the circular portions 150 of the cranks. Sleeves 154 are normally cylindrical in form, and are employed so that when bolts 152 are tightened, the sleeves 154 will be compressed and forced to conform to the irregular configuration of shaft 142 and to expand into slot 146 of the crank, so as to form a driving connection between the shaft and each crank. This type of connection of the cranks to shaft 142 not only permits adjustment of the cranks to any desired angular position relative to the shaft, in order to provide for simultaneous opening and closing of the disconnect switches, but also provides additional shock-absorbing protection because of the resilient nature of sleeves 154. It will be observed that the actual drive connection of cranks 144 and 147 with shaft 142, is formed after the cranks have been adjusted to the desired angular position, by taking up bolts 152. This tightening of bolts 152 acts to deform sleeve 154 to actually form key portions entering into slots 146 as illustrated, and deforms the inner surface of the sleeve into the same D shape as the shaft. Moreover, this drive connection of cranks 144 and 147 with shaft 142 may be formed at any desired angular position by merely taking up bolts 152.

It will be apparent from the foregoing that the switching apparatus described herein is provided with means for causing a high-speed operation of movable switch contacts when moved in one direction, and is adapted to be latched by trip-free latch means at one position to enhance the high-speed operation from this position. Moreover, when the high-speed switch movement is abruptly halted, certain dashpot means is provided for absorbing some of the energy, and a particular means is provided for positively preventing rebound of the parts moving at high speed when they are suddenly stopped. The structure illustrated is embodied in a three-pole switching arrangement wherein it has certain novel features of cooperation. In addition to the shock-absorbing and rebound preventing means, there is also provided an arrangement for obtaining ready adjustment of the operating mechanism to insure simultaneous operation of the 70 movable switch contacts.

Having described preferred embodiments of the invention in accordance with the patent statutes, it is desired that this invention be not limited to these particular structures, inasmuch as 75

it will be apparent to persons skilled in the art that many modifications and changes may be made in the structures disclosed herein, without departing from the broad spirit and scope of the invention. Thus, although the invention is illustrated in connection with disconnect switches, it is apparent that it may also be employed with other types of circuit makers and breakers as covered in the following claims.

10. I claim as my invention:
1. In a circuit interrupter, separable contact means, actuating mechanism for moving at least one of said contact means relative to the other in at least one direction at high speed, means for abruptly halting said high-speed movement, freely movable rebound-preventing means positioned in the path of movement of a part movable with said mechanism and said one contact means at a point adjacent the end of said high-speed movement so as to be engaged with an impact by said part at said point in its opening movement to be moved beyond its movement with said part to a position where it is in the path of return movement of another part movable with said mechanism and one contact means, for momentarily positively blocking rebound of said movable contact means, and said rebound-preventing means being biased to occupy a non-blocking position at all other times.
  2. In a plural phase circuit interrupter, separable contact means for each phase, common actuating mechanism for moving at least one contact of each phase relative to the other contact of each phase in at least one direction at high speed, means for abruptly halting said high-speed movement, means actuated by a part movable with said mechanism and said one contacts for positively blocking rebound of said movable contacts, said blocking means comprising a movable latch member, said latch member being biased to normally occupy a position outside the path of movement of a cooperable latching portion which is movable with said mechanism and movable contact means, said latch member having a portion positioned in the path of movement of said part adjacent the end of its path of high-speed travel to be engaged thereby to move said latch member against its bias temporarily into engagement with said latching portion.
  3. In a circuit interrupter, separable contact means, actuating mechanism for moving at least one of said contact means relative to the other in at least one direction at high speed, means for abruptly halting said high-speed movement, means actuated by a part movable with said mechanism and said one contact means for positively blocking rebound of said movable contact means, said blocking means comprising a movable latch member, said latch member being biased to normally occupy a position outside the path of movement of a cooperable latching portion which is movable with said mechanism and movable contact means, said latch member having a portion positioned in the path of movement of said part adjacent the end of its path of high-speed travel to be engaged thereby with an impact to move said latch member against its bias temporarily beyond the end of the path of movement of said part to a position into engagement with said latching portion, whereby rebound of said mechanism and movable contact means is prevented, and after which said latch member is returned to its normal position by its bias.
  4. In a circuit interrupter, separable contact means, actuating mechanism for moving at least

one of said contact means relative to the other in at least one direction at high speed, means for abruptly halting said high-speed movement including fluid dashpot means comprising a closed dashpot cylinder member, a dashpot piston having an actuating member slidably mounted through an aperture in a wall of said cylinder member, said actuating member being positioned to be engaged by a part movable with said mechanism and said one contact means at a point adjacent but spaced from the end of high-speed movement thereof, baffle means in said cylinder member between said piston and said aperture, and tapered means on said piston adapted to progressively decrease the clearance with said baffle means during actuation of said actuating member to prevent the forcing of liquid out through said aperture upon actuation of said dashpot means and to progressively increase the resistance of said dashpot means.

5. In a disconnect switch, line contact means, blade means mounted for movement into and out of engagement with said contact means, spring means biasing said blade means for movement into engagement with said contact means, motive means for moving said blade means in the opposite direction and charging said spring means, latch means connecting said blade means to said motive means, means for releasing said

latch means to permit rapid closing of said switch, means for abruptly halting closing movement of said blade means at the closed circuit position, means for preventing rebound of said blade means from its closed circuit position including movable blocking means biased to a non-blocking position, means responsive to circuit closing movement of said blade to temporarily move said blocking means into the path of rebound movement of a part movable with said blade means so that rebound is prevented and said blocking means automatically returns to its non-blocking position after danger of rebound is past.
